UNITED STATES PATENT OFFICE.

ASBJÖRN SÖNSTHAGEN, OF WEST EALING, LONDON, ENGLAND.

COATING OR DECORATING APPARATUS.

Application filed September 27, 1919. Serial No. 326,706.

To all whom it may concern:

Be it known that I, ASBJÖRN SÖNSTHAGEN, a subject of the King of Norway, residing at 35 Drayton Grove, West Ealing, London, 5 England, have invented certain new and useful Improvements in Coating or Decorating Apparatus, of which the following is the specification.

This invention relates to apparatus for 10 forming, coating or decorating sweetmeats or other articles or bodies, and it refers to apparatus of the type forming the subject of British Letters Patent granted to me under Number 28948 of 1913, in which a number 15 of nozzles are mounted upon a carriage which is capable of motion in all directions and through which nozzles a stream of material, in a more or less viscous state is directed to form or decorate the bodies as the case 20 may be.

The present invention has for its object certain improvements designed to simplify the construction of machines such as that referred to and which improvements may in 25 part be applied to and used in conjunction with the apparatus forming the subject of the aforesaid British Letters Patent No. 28948 of 1913.

According to the present invention I employ 30 a hopper or container for the material which hopper is so mounted and supported that it is capable of universal movement, and which hopper is heated in any convenient manner, for example by an electric resistance, in order to keep the contents thereof at a temperature sufficient to maintain it in the desired liquid or viscous condition. The 35 hopper or container is mounted upon a shaft or spindle which may conveniently be operated by foot power or by means of an electric or other motor and upon which shaft the said container is mounted in a manner such that it may be swung by means of a suitable handle in a plane at a right angle 40 to the line of said shaft or moved lengthwise thereof.

The hopper at its lower end is funnel shaped and has an opening or openings formed therein through which, as will be 45 presently more fully described, the contents may be allowed to escape.

Running along the bottom of the hopper and disposed contiguous to the opening, is a shaft receiving motion by means of belt or 50 other suitable gearing from the spindle from

which the hopper may be suspended. The shaft forms a closure for the discharge opening or openings in the hopper and it has formed upon it circumferential channels or grooves which may be of any desired cross sectional outline, and which channels form passages permitting the escape of the contents of the said hopper, the diameter of the main or unchannelled portion of the spindle being greater than the width of the discharge opening in the said hopper, said unchannelled portions preventing the passage of the material through the discharge opening.

Provision is made by means of scrapers 70 for ensuring the removal and discharge of the material from the grooves in the roller, and means is also provided for regulating the amount of material in the grooves of the said roller.

In order that the invention may be the better understood drawings are appended in which:—

Fig. 1 is a side view of a machine according to this invention.

Fig. 2 is a plan.

Fig. 3 is an end view seen from the outer end of the hopper.

Fig. 4 is a view to a larger scale showing the inner end of the hopper.

Fig. 5 is a view showing the outer end of said hopper.

Fig. 6 is a side view.

Fig. 7 is a cross section.

Fig. 8 is a side view showing more clearly 90 one of the scrapers and the support therefor.

Fig. 9 is a plan of the underside of the hopper.

Fig. 10 is a plan of the top of the hopper.

Fig. 11 is a side view, showing an arrangement whereby the roller is driven by foot power, and

Fig. 12 is a sectional view showing more clearly the arrangement of the brake, whereby the speed of motion of the hopper may be 100 controlled.

Referring to the accompanying drawings, 1 indicates a pedestal upon which is adjustably mounted by means of the screws 2 and nuts 3, a tubular column 4. The column 4 at its upper end is provided with bearings for a shaft 5 provided with the usual fast and loose pulleys indicated respectively by 6 and 7 and upon which shaft are also mounted pulleys 8 whereby motion may be im- 110

parted through a belt 9 to other pulleys 9^a upon a shaft 10.

Projecting from column 4 is a bar or rod 11 to which are pivotally connected the upper ends of links or rods 12 which links or rods at their lower ends are pivotally connected to lugs 12^a upon the ends of the hopper 13. The hopper comprises a body portion 13 to which is applied an outer casing 13^a as shown more clearly in Fig. 7 said casing being spaced a suitable distance from the body 13 to accommodate a coil 14 which entirely surrounds the body 13 and through which a heating or cooling medium may be caused to circulate. Where a heating device is employed the boiler or the like, not shown, may conveniently be supported upon the pedestal at the point 4^a. The lower end of the outer casing is supported in spaced relationship to the body 13 of the hopper by means of the distance piece *a* connected by rivets or the like to the body 13 and said casing 13^a. The lower end of the body 13 terminates in an extension 13^b having at the bottom an opening 13^c in the end walls of which are formed openings for the ends of the roller 16. The openings for the end of the roller are of such size and outline as to permit of slight movement of the roller, laterally of the hopper as will be presently more fully described.

The extension 13^b is clamped to the lower end of body 13 by means of the strips 13^d secured to the horizontal member of the aforesaid distance piece *a* by the bolts 13^e. The strips 13^d have their inner faces bevelled or inclined to engage the inclined outer surface of the extension 13^b which is thus firmly clamped to the body of the hopper. The inner surface of the extension 13^b is curved as shown to a radius approximately equal to the radius of the roller 16 so that it is closely contiguous to said roller so as to prevent the escape of the contents of the hopper at this point. 14 indicates guides formed upon or secured to the ends of the hopper 13 slotted to permit the passage of the aforesaid links 12 and which guides assist in retaining the hopper against rotary motion. The links 12 are also supported by means of the bar 14^a Fig. 1 carried by column 4 and slotted to permit the passage of the said links.

Pivotally mounted at each end of the hopper upon studs 14^b are plates 14^c provided with bearings 14^d for the support of the ends of the roller 16 running longitudinally of the hopper and disposed adjacent the discharge opening. Mounted at one end of the roller 16 is a pinion 17 engaging a pinion 18 mounted upon one of the studs 14^b. The plates 14^c swing upon their pivots so that when required the roller may be lowered to bring it nearer to the mouth of the hopper so that as the roller wears it may be adjusted

to prevent escape of the material from that side of the roller in immediate proximity with the inner surface of the mouth of the said hopper.

The plates 14^c lie in close contact with the outer surface of the hopper so that they act to prevent the escape of the contents through the openings through which the ends of roller 16 pass.

The plates 14^c after adjustment may be held against further movement by clamping screws or the like 20 which engage slots 21 in arms 22 of said plates 14^c, see Figs. 6 and 7. Motion is imparted to the pinion 18 by means of the chain wheel 18^a secured thereto and around which passes a chain 18^b receiving motion from a chain wheel 18^c upon the main shaft 5. The roller 16 is provided in the present instance with peripheral grooves 23 and engaging the outer surface of the said roller is a plate 24 adjustably mounted upon one side of the mouth of the hopper. Mounted upon bearings 14^d are bosses 25 connected by means of a bar or rod 26 by means of which said bosses may be simultaneously rotated. The bosses 25 are provided with lugs 27 slotted to receive the ends of a rod 28, shown more clearly in Fig. 8 which is clamped at its ends to the lugs 27 by means of nuts 29. The rod 28 has formed upon it at equidistant intervals flats 30 to which are clamped by means of screws 31 plates 32 forming scrapers and which scrapers engage the aforesaid grooves 23 and serve to effect the removal of the material therefrom. Springs such as 33, shown more clearly in Fig. 5 are interposed between lugs 33^a and 33^b formed respectively upon plates 14^c and bosses 25, which springs serve to keep the scrapers always in contact with the grooves. Projecting from one side of the hopper are lugs 34 perforated for the passage of pins 35 which pins pass through bosses 36 formed on a rod 36^a connected at its inner end to a crankpin 37 adjustably mounted upon a disc 37^a. The disc 37 is mounted upon a shaft 38 carried in bearings formed in lugs 39 projecting from the tubular column 4 aforesaid. Secured to the shaft 38 is a bevel wheel 39^a engaging a second wheel 40 mounted upon shaft 10 before referred to.

In order that the speed of the shaft (5) may be varied, and with it, that of the roller (16), a brake is provided comprising a strap (41) one end of which is secured to a pin (41^a) carried by a boss (41^a) projecting from column 4. Mounted on the aforesaid pin is a lever (41^b) to one end of which is connected a cord or other flexible body (42) which is led round a guide pulley (45) to a hand lever (46^a) fulcrumed on one side of the table (42^a), supported by the legs (44^a), on which table the bodies to be coated are placed. The band (41) passes round a

drum (41^c) on shaft 10 and is connected to a pin (41^d) projecting from the face of the aforesaid lever (41^b).

It will be seen from the foregoing description that as motion is imparted to the shaft 5 it will be transmitted through chain 18 to the roller 16 which rotating in the hopper will convey a certain quantity of the material therein by means of grooves 23 to the 10 outside of the hopper where it is removed in the form of long narrow strips by the scrapers 32 and falls upon a table not shown, but disposed beneath the hopper and upon which table the goods to be decorated or 15 coated are placed. At the same time the shaft 38 will be caused to rotate through the pulleys 8, 9^a and bevel wheels 39^a and 40. A rocking motion will thus be imparted to the hopper by the rod 36 whereby a pattern 20 or figure will be produced for ornamenting the goods. If desired, one of the pins 35 may be removed whereby a lateral motion may be imparted to the hopper which will again cause a variation in the pattern or 25 ornamentation produced. Again the rod 36 may be entirely disconnected from the hopper which will then be stationary or can be operated by hand to produce any desired pattern or figure. As the speed of motion 30 of the hopper may be controlled by means of brake 41, it is evident that a great variety of patterns or figures may be produced. The handle 26, when the movements of the hopper are hand-controlled, is utilized not only 35 to control the passage of the material from the feed roller but to effect the movements of the said hopper.

As already stated, the roller within the hopper, may be driven by foot power in 40 which case a treadle (44^a) may be provided pivotally connected by means of a rod (45) supported with a band-wheel or pulley (46) supported from the pedestal (1). Motion is transmitted by a belt (48) from the pulley (46) 45 to a second pulley (47) mounted upon the aforesaid spindle or shaft (5) to which is secured the chain wheel (18^c) before referred to, and from which motion is transmitted by chain (18^b) to chain wheel (18^a).

50 Instead of or in addition to means for heating the contents of the hopper, provision may be made for cooling same.

I may if desired provide for the admission of compressed air to the hopper.

55 Claims.

1. A machine for decorating, forming or 60 coating sweetmeats comprising a hopper so supported as to be capable of movement by hand in horizontal directions and a roller located in the hopper for removing the material therefrom, means for securing the discharge of material from the roller, such means controlled by the same hand.

2. A machine for decorating, forming or 65 coating sweetmeats comprising a hopper so

supported as to be held against turning movement and capable of movement in all horizontal directions and a roller located in the hopper for removing the material therefrom, means for securing the discharge of 70 material from the roller, such means controlled by hand.

3. A machine for decorating, forming or 75 coating sweetmeats comprising a hopper so supported as to be held against turning movement and capable of movement of translation by hand in horizontal directions and a roller located in the hopper for removing the material therefrom, means for securing the discharge of material from the 80 roller such means controlled by the same hand.

4. A machine for decorating, forming or 85 coating sweetmeats comprising a hopper so supported as to be capable of movement by hand; a roller located in said hopper, hand-controlled means for removing the material therefrom, said hopper and means being adapted for simultaneous control by the 90 same hand.

5. A machine for decorating, forming or 95 coating sweetmeats comprising a hopper so supported as to be capable of movement by hand in horizontal directions, a roller located in the hopper; hand-controlled means for moving the material therefrom, both the movement of the hopper and the discharge of material therefrom being controlled by one hand; and a hand brake for regulating the speed of removing material from 100 the hopper.

6. A machine for decorating, forming or 105 coating sweetmeats comprising a hopper so supported as to be capable of movement by hand and foot-driven means located in the hopper for removing the material therefrom, such means being also controlled by hand.

7. A machine for decorating, forming or 110 coating sweetmeats comprising a hopper so supported as to be capable of movement by hand in all horizontal directions and foot-driven means located in the hopper for removing the material therefrom, such means being also controlled by hand.

8. A machine for decorating, forming or 115 coating sweetmeats comprising a hopper so supported as to be capable of movement by hand in horizontal directions and foot-driven means located in the hopper for removing the material therefrom, such means being also controlled by hand, and a hand-brake for regulating the speed of removing material from the hopper.

9. A machine for decorating, forming or 120 coating sweetmeats comprising a hopper so supported as to be capable of movement in all horizontal directions, a discharge opening in said hopper, a feed roller adjacent said opening, peripheral grooves in said 125

roller, scrapers engaging said grooves to remove the material therefrom, a handle for moving said hopper said handle also controlling the position of the scrapers to vary the amount removed from the hopper.

10. A machine for decorating, forming or coating sweetmeats comprising a hopper so supported as to be capable of movement in all horizontal directions, a discharge opening in said hopper, a feed roller adjacent said opening, peripheral grooves in said roller, scrapers engaging said grooves to remove the material therefrom, hand actuated means for operating the scrapers to vary the amount of material removed from the roller, means for effecting the movement of said hopper, a hand controlled brake for regulating the speed of movement of the hopper.

11. A machine for forming, decorating or 20 coating sweetmeats, comprising a hopper so supported as to be capable of movement in all horizontal directions, a discharge opening in said hopper, a feed roller adjacent 25 said opening, peripheral grooves in said roller, foot driven means operating said roller, scrapers engaging said grooves to remove the material therefrom, a handle for moving said hopper said handle also controlling the position of the scrapers to vary 30 the amount removed from the hopper.

In testimony whereof I affix my signature in the presence of the two undersigned witnesses.

ASBJÖRN SÖNSTHAGEN.
